RECEPTACLE OPENER

Seymour Batdorf, Lancaster, Pa., assignor to Liberty Can and Sign Company, Lancaster, Pa., a corporation of Pennsylvania

Application May 8, 1935, Serial No. 20,496

3 Claims. (Cl. 220—43)

This invention relates to receptacle openers of the pry-bar type for cone-type friction seal plugs employed to close or seal such receptacles, and also to the combination of such an opener with 5 a special construction of such a sealing plug.

The primary objects of the present invention are to provide such an opener which may be freely moved peripherally about the rim or bead of the plug to be used to successively pry against 10 the end of the receptacle at different points adjacent the periphery of the plug and which will remain at all times permanently though loosely applied to the plug so as to be removed therewith and applied therewith to the receptacle, whereby 15 the receptacle may be opened and resealed repeatedly a number of times and the opener will always be available to facilitate the opening; to provide such an opener which will not injure the top of the receptacle nor scratch or mar the 20 finish of the said top; to provide an opener having a stiffly resilient prying leg and foot bearing with a cam action on the top of the receptacle and exerting a spring pressure in the final stages of its operation to aid in lifting the sealing plug, 25 such resilient characteristic also contributing to the avoidance of marring the finish of the top of the receptacle; to provide such an opener which will not tightly frictionally engage any edge, face or portion of the plug or top of the receptacle in 30 its retracted or inoperative position or in any intermediate position when not exerting intentionally a lifting leverage on the top of the receptacle, whereby the opener may be freely and easily shifted in a peripheral direction from point 35 to point about the periphery of the sealing plug without jamming or binding or sticking in one position and without risk of being damaged or twisted by the exertion of too much force by the 40 operator in his impatience in trying to shift it peripherally and which, if the opener jammed in position might result simply in twisting the opener off of the plug and destroying its further usefulness instead of sliding it peripherally about the plug as intended; to so form and combine the 45 opener and plug that in the normal inoperative or storing or shipping position of the opener the parts of the opener extending beyond the plug and the parts of the opener extending below the rim of the plug will not interfere with the proper 50 complete seating or sealing of the plug in its opening; and to so form and combine the opener and the plug that their associated interengaging elements responsible for maintaining their permanent loose connection will be safeguarded against 55 excessive movement of the parts which might

result otherwise in their deformation and separation.

Herein I illustrate and describe simply the present preferred embodiment of my invention merely by way of illustration of the practice of my invention as by law required. However, I am well aware that my invention is capable of various embodiments and that the several details thereof may be modified in different ways, all without departing from my said invention, and, therefore, the accompanying drawing and description herein are to be considered as merely illustrative and not exclusive.

In the accompanying drawing:

Figure 1 represents a top plan view of a receptacle with a sealing plug and opener embodying my invention applied thereto;

Figure 2, a sectional view on line 2—2 of Fig. 1, looking in the direction of the arrows;

Figure 3, a view similar to Fig. 2, the opener being in intermediate position;

Figure 4, a view similar to Fig. 2, the can body being omitted and the lifter or opener shown in its extreme outwardly rotated or lifting position; and

Figure 5, a sectional view on line 5—5 of Fig. 1 showing the slightly arched and rib braced and stiffened construction of the lifter lever F.

Referring now in detail to the drawing, A designates the body of a can or receptacle; B, 30 the top thereof; C, the usual end seam; D, the usual very slightly downwardly tapering or cone form seat defining the receptacle opening; E, the usual cone type sealing plug or closure of the friction sealing type making a tight sealing fit in said seat; and F, the handle or main operating lever of the lifter or opener.

The lever F is formed of relatively heavy stiff sheet steel, or preferably so, and its radially outer portion is preferably slightly upwardly arched or curved in cross-section and preferably formed with an upwardly pressed longitudinally extending rib f to stiffen and strengthen it lengthwise and it will preferably be so formed and bent lengthwise that no part of the lifter will extend 45 above the top of seam C and so that the inner portion of the lever F will rest on the top of the plug E while the extreme inner end portion will be bent up away from the upper face of the plug E to facilitate the grasping and movement of the 50 lever F incident to its opening or lifting operation.

The radially outer portion of the lever F lies or rests against the top surface of the upwardly and outwardly curved and flaring peripheral rim 55

- e of the plug E and at this point is provided with preferably integral side extensions 5, the radially outer portions of these extensions 5 being separated by a cut or slot from the rest of the lifter 5 and being downwardly and radially inwardly bent to constitute retaining and thrust hooks or fingers 7, and the radially inner portions of said side extensions are bent downward to constitute retaining lugs 9 in any given position of rotation 10 of which in a vertical plane about the rim of the plug E some portion of their radially outer faces will contact with some portion of the radially inner face of the wall of the plug E or of its rim e to prevent the radially outward movement of 15 the hooks or fingers 7 to such extent that their radially inner ends will clear the edge 6 of the open external bead or curl e' of the plug E. In other words the function of the lugs 9 is to limit the radially outward movement of the lifter as 20 a whole so as to prevent its separation from the plug E. In view of the fact that the plug E is of general frusto-conical form and is curved in cross-section adjacent the point of mergence between its side wall and bottom, the lugs 9 will 25 preferably not be truly vertical but will preferably incline downwardly and inwardly to lie substantially parallel to the adjacent opposed portion of the vertically disposed or inclined portion of the plug and will have their lower ends bent inwardly slightly, so that when the lifter is in normal position with its inner end resting on the upper face of the plug E, as illustrated in Fig. 2, the lugs 9 will lie very close to the wall of the plug E but will not be in contact, or in substantial contact therewith, whereby the lifter 30 may be shifted in either peripheral direction about the plug E without jamming and the risk of being deformed, twisted, or torn off such as might occur were the lugs 9 bent down straight 35 or their lower ends not bent inwardly to avoid relatively tight frictional engagement with the wall of the plug E interfering with or preventing free peripheral sliding movement of the lifter as a whole in its normal position.
- 40 The lever F is formed with a preferably integral radially outward extending portion extending beyond the side extensions 5 and constituting a prying arm 4, which is preferably slightly upwardly arched in cross-section and preferably has a longitudinally extending reinforcing rib f to give it strength and rigidity and being in this respect simply a continuation of the lever F. A preferably integral stiff preferably semi-rigid preferably slightly resilient lifter leg 2 depends 45 downwardly almost vertically from the outer end of arm 4 on an abrupt curve and is inclined very slightly radially outwardly to its lower end where it is provided with an abrupt bend to give a curved bearing portion 3 which is continued upward by a short foot 4 closely approaching the vertical and yet very slightly inclined radially outwardly and upwardly, said foot 4 and the curved or bent portion 3 preferably being also of the same preferably semi-rigid preferably 50 slightly resilient construction and material as the leg 2 and preferably being integral therewith.
- 55 Preferably the radially inner end portions of the fingers 7 will be reduced in thickness in vertical cross-section, as illustrated, to avoid interfering with the proper seating of the sealing plug E.
- 60 Preferably the plug E will be formed with an external bead or limit and sealing face adjacent its rim e, said external bead or shoulder 8 having 65 its lower face located below the lowest portions

of the fingers or hooks 7, or such portions thereof as otherwise might be interposed between, and engaged on opposite faces by, the opposing faces of the rim of said plug E and the top of the can, and so prevents interference by said fingers or hooks 7 with the proper seating and sealing of the plug E. Of course, in such case, the conical portion of the vertically inclined wall of the plug E below said shoulder or bead 8 will be made of such size and shape as to make a tight 10 frictional sealing fit in the seat D.

15 Of course it would seem apparent that the shoulder, if employed, may be formed in any suitable or practical and known manner, as by forming a bead 8 as illustrated or by making a two 20 diameter plug, the inward offset between the large and small diameters forming the shoulder 8, or substantially the same result might be accomplished by suddenly increasing the upward and outward flare of the cone to abruptly change the 25 angle of the external cone face, the form and relationship of the hooks or fingers 7 and lugs 9 being modified as might be made necessary by any such changed cross-sectional form of the wall of the plug E in order that their functions 30 may be retained unimpaired.

35 In operation, with the plug E driven tightly home into frictional sealing contact with its seat D and with the parts in normal position as illustrated, it being desired to lift the plug E out, the inner end of the lever F is gripped and rotated about the rim e until the rounded face 3 engages the upper face of the top B and at which time the fingers 7 will be hooked under the curl 6 with their tips thrusting against the external upper 40 portion of the plug E at its point of mergence with the rim e, and continued vertical movement or rotation of the lever F will cause the cam surface 3 to swing about the tips of said fingers 7 as a sliding fulcrum point as said cam surface 45 40 itself moves in sliding contact as a fulcrum point with the top of the can exerting a radially inward and upward thrust against the upper part of the plug E in an inclined straight line extending from the point of contact between the cam face 3 and the top B of the can to the point of contact between the tips of fingers 7 and the upper part of the plug E, the position and inclination of said line of thrust shifting progressively as the lever F is rotated through its range of operative movement.

50 As the lever F is thus moved or rotated about the rim e of plug E to lift the latter the leg 2 will move into substantially vertical or slightly past vertical position by the time the curved or cam portion 3 touches the top of the can, so that further rotation of the lever F, particularly in case the plug E has a real tight frictional seat in, and is tightly gripped by, the seat D, will bend the leg 2 inward toward the plug E slightly so 55 putting it under compression or storing energy in it, which energy subsequently acts to force the plug E upward from its seat once the initial tight frictional grip is overcome. Also, this stiffly resilient quality of the leg 2 and its foot 4 permits the same to yield slightly and thus renders less the risk of marring the top when considerable force is necessary to overcome the frictional grip between the plug E and its seat D.

60 By not tightly pressing the bead e' against the under face of the rim e I leave a partially open bead or curl having a radially inwardly presented edge face 6 vertically spaced from the lower face of the rim e and extending in the path of the upper ends of the fingers 7 when in the position 70 75

illustrated in Fig. 4 and so preventing the separation of the lifter from the plug E by radially outward movement of the lifter in the horizontal plane of the plug E when the parts are in such relationship, and the curved or cam face 3 engaging with the external face of the cone portion of the plug E when moved to the position illustrated in Fig. 4 prevents the further movement of the lifter with relation to the plug E in that direction to such position as might permit separation of the lifter from the plug.

I claim:

1. A friction closure plug for a receptacle having an opening defined by a frictional sealing seat, said plug having a vertically extending wall and being formed with a radially outwardly extending rim and with a flange integral with said rim and presenting an annular stop shoulder spaced vertically downwardly away from said rim and radially outwardly from the opposed vertically extending wall of said plug, in combination with a receptacle opener comprising a substantially rigid operating lever, a leg integral with and extending substantially vertically downward from said lever, a stiffly resilient prying foot integral with said leg and extending upwardly and radially outwardly therefrom, a rounded cam face formed at the point of mergence of said foot and leg, and means carried by said lever to loosely slidably permanently connect said lever about the rim portion of said plug for free sliding and partial rotary movement in different planes, said means comprising a part extending up inside of said continuous shoulder and engaging the face thereof in one position of the lever to prevent separation of said opener from said plug.

2. A friction closure plug for a receptacle having an opening defined by a frictional sealing seat, said plug having a vertically extending wall and being formed with a radially outwardly extending rim and with a flange integral with the outer portion of said rim and presenting a continuous stop shoulder spaced vertically downwardly away from said rim and outwardly from the opposed vertically extending wall of said plug,

in combination with a receptacle opener comprising an operating lever, a leg integral with and extending substantially vertically downward from said lever, a stiffly resilient prying foot integral with said leg and extending upwardly and radially outwardly therefrom, a rounded cam face formed at the point of mergence of said foot and leg, and means carried by said lever to loosely slidably permanently connect said lever about the rim portion of said plug for free sliding and partial rotary movement in different planes, said means comprising a part extending up inside of said continuous shoulder and engaging the face thereof in one position of the lever to prevent separation of said opener from said plug.

3. An opener for a receptacle closed by a plug having a peripheral annular bead, said opener comprising an operating lever, and prying means integral with and depending from said lever said prying means comprising a leg integral with and extending substantially vertically downward from said lever, a stiffly resilient prying foot integral with said leg and extending upwardly and radially outwardly therefrom, and a rounded cam face formed at the point of mergence of said foot and leg, in combination with a finger integral with said lever and extending radially outwardly beyond the bead of said plug and down inwardly below said bead, and a lug integral with said lever to loosely engage the inner face of said plug, said finger and lug being so formed and in such spaced relation to each other that in any given position of the lever some portion of said lug will engage some opposed face portion of the plug before the finger has been moved to such position that it will clear the bead by movement of the lever as a whole in any given direction with relation to the plug, and said prying means being of such length and so disposed relative to said finger and lug that it will engage an opposed face of the plug to prevent continued movement in the same direction of the lever after said finger has moved into engagement with the radially inner face of said bead.

SEYMOUR BATDORF.
